UNITED STATES PATENT OFFICE.

WILLIAM ALFRED PORTER, OF BRISBANE, QUEENSLAND, AUSTRALIA, ASSIGNOR OF
ONE-HALF TO WILLIAM VALENTINE SCANLAN, OF BRISBANE, AUSTRALIA.

APPARATUS FOR MAKING HOLLOW BENDS, ANGLES, OR SUCH LIKE BODIES OF CONCRETE OR OTHER MATERIAL.

Application filed June 30, 1926, Serial No. 119,729, and in Australia August 26, 1925.

It has, for some time past, been possible to manufacture pipes of concrete or other material or mixture of such a density as to enable them to resist, to a certain extent, 5 external and internal pressure, and prevent, to a very great extent, leakage of any fluids which may be passing through. So far as I am aware, it has not been possible to manufacture hollow bends, angles, junctions, and other such ducts or mouldings 10 wherein the material is of a similar density except by the vibratory process, which is slow, and the articles, when produced, invariably contain pores which are a cause of 15 weakness.

The object of this invention is the production of a machine whereby these articles can be made free of pores and in very much less time.

20 In carrying out my invention I provide a number of rectangular or otherwise suitably shaped plates of iron or suitable material, mounted upon a wooden or other suitable base forming a mould box in which the 25 articles are moulded and which are bolted or otherwise secured together and are carried in a suitable frame so that they can be rotated at the desired speed. These mould boxes have a central hole or passage through 30 them, and radiating therefrom or arranged tangentially thereto is a number of moulds of the required shape and size, in which the bends or angles or other articles are formed. The cores are carried by suitable means. 35 The moulds may be formed in each face of the plates so that each plate may carry two half moulds. As an alternative, I may form the moulds in a solid mass, of iron, concrete, or other material, instead of in the 40 face of the plates.

To the mould boxes are fitted sectional cover plates, either singly or in sets, and these mould boxes are assembled in a separable cylinder or otherwise held in position 45 so that they may be spun round at any desired speed and by any suitable means.

To fully describe the invention reference is now made to the accompanying drawings, in which:

50 Fig. 1, is a perspective view showing two sets of plates bolted together.

Fig. 2, is a plan view of a plate showing the moulds for making bends.

Fig. 3, is a perspective view of cover for one side for one set of plates. 55

Fig. 4, is a cross section of cover, moulded article, and core.

Fig. 5, is an elevation of core.

Fig. 6, is an end view of core.

Fig. 7, is an end view of mould box and cover to reduced scale.

Fig. 8, is an elevation of frame.

Fig. 9, is a cross section of mould box showing frame fitted in the central passage. 65

Fig. 10, is a perspective view of a separable casing for assembling the mould boxes.

Fig. 11, is a longitudinal section of separable casing showing mould boxes assembled.

Figs. 12 to 15 are elevations of various 70 articles.

The reference numerals serve to indicate like parts in all figures.

1 are the mould plates and 1^a their bases, 2 the central passage through the mould 75 boxes, 3 the moulds, 3^a the moulded article, and 4 rubber washers, or other insertion to prevent any leakage of the material used.

6 is a section of the cover plates, which are kept in place on the mould boxes by 80 dowels 7 fitting into holes 8 in the underside of the cover plates, and secured by studs 9 and turn buttons 10. Two or more of the half moulds are bolted together by bolts and nuts 11. 85

The cores are made in three sections consisting of two outer sections 12 and a central tapered section 13, by which the outer sections are locked together. This provides a collapsible core, which can be easily withdrawn from the moulds. 90

14 is a hinged cylindrical or other casing for assembling the mould boxes, the two halves of which are clamped together, 15 indicates the hinge, and 16 the clamping flange. 95 If of shape other than cylindrical, circular tracks would be formed or secured thereon so as to facilitate rotation.

As an alternative arrangement, the cylindrical or other casing may be dispensed with 100 and circular end plates secured at each end of the units of moulds. In this, as well as the arrangement where the casing is used, dowels and dowel holes may be provided in the respective faces of the mould, so as to 105 ensure their correct registration.

17 are flanges which fit inside the cylinder and which are clamped thereto by bolts 18.

The central passages 2 through the two end mould boxes assembled in the casing are fitted with square metal frames 19 with rounded corners held to mould boxes by lugs 20 and turn button 21. These frames contract the size of the holes, prevent the filling material from escaping, and enable the same to be fed into the mould boxes from both ends of the casing, and, when removed, provide for the removal of the slurry or any over-plus of material fed to the moulds.

In using the invention, I prefer to secure 15 two half mould boxes together by the cover plates 6, which then form a unit. I then assemble a number of these units and secure them together by bolts and nuts 11 and fit them into a separable cylinder by clamping 20 the cylinder together by clamps or by other suitable means. The assembled units are then rotated at a high speed and the concrete or other material, as it is fed into the central holes of the units, is, by centrifugal force, 25 thrown outward in the respective moulds. When the moulds are filled, the moulded articles are allowed time to set, and, by disassembling the mould boxes and removing the cores, the moulded articles can be withdrawn 30 from the moulds.

Slight modifications may be resorted to without departing from the spirit or scope of the invention.

What I claim as my invention, and desire 35 to secure by Letters Patent is:—

1. In improvement in apparatus for making hollow bends, angles or such like bodies

of concrete or other material, the combination of mould boxes consisting of half moulds formed of the required shape held together 40 by sectional covers and provided with a central feed hole as and for the purpose set forth and as herein described.

2. In improvement in apparatus for making hollow bends, angles or such like bodies 45 of concrete or other material, the combination of mould boxes and cover plates as claimed in claim 1 with collapsible covers as herein described.

3. In improvement in apparatus for making hollow bends, angles or such like bodies 50 of concrete or other material, the combination of mould boxes, cover plates and cores as claimed in claim 1 in combination with a separable casing provided with end flanges 55 as herein described.

4. In improvements for making hollow bends, angles or such like bodies of concrete or other material the combination of mould boxes consisting of half moulds formed of 60 the required shape held together by sectional cover plates, means for attaching the said plates to the mould boxes, and collapsible cores, said mould boxes provided with a central hole as herein described. 65

5. In improvements for making hollow bends, angles or such like bodies of concrete or other material the combination of mould boxes, cover plates and cores as claimed in 70 claim 1 in combination with a separable casing provided with flanges as herein described. 79

In testimony whereof I affix my signature.

WILLIAM ALFRED PORTER.
